UNITED STATES PATENT OFFICE.

EDWARD J. CONNOLLY, OF DETROIT, MICHIGAN, ASSIGNOR TO C. R. WILSON BODY COMPANY, OF DETROIT, MICHIGAN, A CORPORATION OF MICHIGAN.

ADJUSTABLE DOOR BUMPER.

Application filed November 27, 1922. Serial No. 608,639.

To all whom it may concern:

Be it known that I, EDWARD J. CONNOLLY, a citizen of the United States of America, residing at Detroit, in the county of Wayne and State of Michigan, have invented certain new and useful Improvements in Adjustable Door Bumpers, of which the following is a specification, reference being had therein to the accompanying drawings.

10 The invention relates to adjustable automobile door bumpers and comprises certain structural features, combinations and arrangement of parts hereinafter fully described and illustrated in the accompanying drawings, wherein:—

Figure 1 is a view of my invention applied to a vehicle door jamb;

Figure 2 is a sectional view taken on line 2—2 of Figure 1;

20 Figures 3, 3^a and 3^b are respectively perspective views of the holder, the rubber insert removed and the angle plate against which the rubber insert abuts.

25 In these views the reference character A designates a motor vehicle door and B the jamb to which said door latches in closed position. C is a bumper or cushioning member formed of rubber or like material and D is a sheet metal holder therefor. The 30 holder comprises a rectangular raised body portion D' which cooperates with the jamb B to which it is attached to form the socket for the cushioning member C. To secure the holder to the jamb the same is provided at 35 both ends with flanges D² which are apertured to receive screws C.

The raised body portion of the holder comprises the side walls D³, top wall D⁴ and rear wall D⁵. The front edge of the top wall 40 D⁴ is turned down slightly to form a depending flange D⁶ which is adapted to engage the cushioning member and lock the same against longitudinal movement.

45 The cushioning member, as shown comprises a resilient block having an enlarged head portion C' and a smaller body portion C². The head portion is wedge shaped at an angle of substantially 90° and is provided with a rounded apex. The body portion is rectangular and of such shape as will conform to the inner surface of the walls of the raised body portion D' into which it is adapted to fit. This body portion C² is however some-

what greater in depth than the raised body portion D' of the holder for a purpose here- 55 inafter appearing.

An angle plate F of approximately 87° is secured to the door of the vehicle by screws F', as best shown in Figure 1. The holder D and cushioning member C are so positioned that when the door is swung to its closed position, the wedge shaped head C' will engage the angle plate F just before the door latches. The particular angle of 60 said head portion and angle plate is important in that it provides cooperation between the parts for forming a wedging engagement with each other.

A further feature of applicant's device is its adjustability. In assembling the device, 70 the portion C² of the cushioning member is placed in the socket formed by the rectangular raised body portion D' of the holder. The holder is then positioned for attachment and the screws inserted. As stated 75 above the portion C² is of greater depth than the body portion D' of the holder and this provides for securely clamping the cushioning member against the jamb B. The depending flange D⁶ is forced into the cushioning member when the screws are tightened 80 and securely locks the same against longitudinal movement until the screws are loosened. To adjust the cushioning member the screws are loosened and the insert pulled 85 forward then the screws are tightened again. In this way the bumper may be adjusted to any desired position by grasping and pulling the wedge shaped head portion forward after which tightening of the screws will 90 firmly clamp the same against the door jamb and imbed the locking flange D⁶ therein.

The particular angle of the angle plate F being less than the angle of the wedge shaped head portion of the bumper, there 95 will be a wedging action between the two when they engage upon closing of the door. This wedging action tends to elongate the wedge shaped head portion, as well as compress the same, thus adding a further cushioning effect.

100 What I claim as my invention is:—

1. In an automobile door bumper, the combination with an adjustable cushioning member comprising a head and body portion respectively, of a member adapted to 105

fit over said body portion, and means for clamping said body portion between said member and the jamb of the door.

2. In an automobile door bumper, the combination with an adjustable cushioning member comprising a wedge shaped head portion and a body portion, of a holder for engaging said body portion, means for clamping said body portion upon the jamb 10 of the door and locking means for preventing longitudinal movement thereof.

3. In an automobile door bumper, the combination with a holder mounted on the jamb of the door, of an adjustable wedge 15 shaped cushioning member secured by said holder, and means mounted upon the door for receiving said cushioning member to form a wedging engagement therewith.

4. In an automobile door bumper, the combination with a cushioning member comprising a wedge shaped head portion and a body portion, a holder for securing 20 said body portion to the jamb of the door and an angle plate of substantially 87° 25 mounted upon the door and adapted to form a wedging engagement with said wedge shaped head portion when the door is latched.

5. An adjustable bumper for automobile 30 doors comprising a cushioning member, a holder adapted to telescopically engage a portion of said member, means upon opposite sides of said holder for clamping said engaged portion between said holder and the door jamb, the unengaged portion of 35 said cushioning member forming a surface adapted to be grasped for adjusting the bumper when the clamp is released.

6. An adjustable bumper for automobile

doors comprising a holder provided with a 40 raised body portion, having apertured flanges upon opposite sides thereof, of a cushioning member provided with a body portion and an enlarged head portion, the body portion of said cushioning member 45 being adapted to fit within said raised body portion of the holder and being of greater width than the walls of said raised body portion, securing means engageable with said apertured flanges for clamping said 50 cushioning member between said holder and the door jamb and a locking flange on said raised body portion engaging said cushioning member.

7. An adjustable bumper for automobile 55 doors comprising a cushioning member, a holder, a raised body portion on said holder comprising side walls, and an end and top wall respectively, a depending flange on said top wall for engaging and locking said cushioning member in predetermined position, and means for moving said depending flange toward and away from said cushioning member.

8. In an adjustable door bumper, the combination with a cushioning member having a wedge shaped head portion, of means for clamping said member upon the jamb of the door, and an angle plate of a less angle than 60 said wedge shaped head portion secured to 70 the door and adapted to receive said head portion when the door is closed, the lesser angle of said angle plate acting to elongate, as well as compress said wedge shaped head upon engagement therewith.

In testimony whereof I affix my signature.

EDWARD J. CONNOLLY.
